UNITED STATES PATENT OFFICE.

OSCAR LINDHOLM, OF CHICAGO, ILLINOIS, ASSIGNOR OF THREE-TENTHS TO ANTON RICKER AND TWO-TENTHS TO GUNARD MAGNUSON, BOTH OF CHICAGO, ILLINOIS.

AUTOMATIC TIME-CONTROLLED DRAFT REGULATOR.

Application filed December 13, 1920. Serial No. 430,130.

To all whom it may concern:

Be it known that I, OSCAR LINDHOLM, a subject of the King of Sweden, residing at Chicago, in the county of Cook and State 5 of Illinois, whose post-office address is No. 2321 South Washtenaw Avenue, in said city, prays that Letters Patent may be granted to him for the Improvements in Automatic Time-Controlled Draft Regulators.

10 This invention relates to improvements in automatic draft regulators for furnaces, boilers and the like, and has reference more particularly to that type of automatic regulator which is controlled as to the time of 15 its operation by an alarm clock, so that the regulator may be set to operate at any predetermined time by setting the alarm of the clock at such time, and will automatically perform its function when the alarm of the 20 clock is released.

So far as I am aware, most clock controlled regulators of this type are positively actuated to open the draft door or damper by means of a weight or spring which is normally held inactive by a catch, and the alarm winder of the clock performs the function of releasing the catch at the proper time and thus permit the weight or spring to act.

25 Devices of this character are somewhat unreliable, mainly for the reason that the catch or lock which holds the weight or spring inactive is not infrequently released by accidental means.

According to my present invention, I 30 provide a continuous operating connection between the draft controlling member and the alarm winder of the clock so that, when the operating spring of the latter is released, it constitutes the motor for directly 35 and positively actuating the draft controlling member, thereby doing away entirely with the presence of weights, springs, and catches, and rendering the operation of the regulator more positive and certain.

40 One principal contemplated application of my invention is an automatic regulator for steam boilers, and for this purpose it is designed to perform the double function of, first opening up the draft at a predetermined 45 hour, established by the clock, and, second, again closing the draft after steam has been gotten up and has reached a predetermined pressure. To this end, the device in its preferred and most complete form is equipped 50 with a clutch mechanism connected to the

lever of the usual automatic diaphragm governor commonly employed on steam boilers, the releasing of said clutch permitting the draft controlling member to return automatically to its normal closed position. 60

From the foregoing it will be evident that the chief objects of the present invention, are, first, to provide an automatic draft regulator which shall be free from the objections inherent in the use of weights, springs 65 and clock controlled catches and shall be positive and certain in its operation by using the spring of the alarm winder as a motor for moving the draft door or other draft controlling element to open position; and, 70 second, to provide an automatic draft regulator which will open the draft at a predetermined time when steam is to be gotten up and will automatically close the draft after the steam has reached a predetermined 75 pressure.

In order to make my invention, and its novel structural features and mode of operation entirely clear to persons skilled in the art, I have illustrated in the accompanying 80 drawings one practical and operative embodiment of the same, and referring thereto.

Fig. 1 is an elevation of an ordinary steam boiler furnace of a type commonly employed for domestic use, showing my invention applied thereto;

Fig. 2 is a side elevation of the clock actuated mechanism for opening the draft door, including a clutch mechanism operated by the diaphragm governor for disconnecting 85 the winding drum from the winding shaft;

Fig. 3 is a top plan view of the parts shown in Fig. 2; and

Fig. 4 is a detail view in longitudinal section through the winding drum, winding 90 shaft and clutch.

Referring to the drawings—

5 may designate as an entirety a steam boiler equipped with the usual hinged draft door 6 covering the opening to the ash-pit, 100 and with the usual diaphragm governor 7 connected to the usual weighted governor lever 8, one end of which latter is in common practice usually connected by a cord or chain to the door 6.

Mounted upon a shelf 9, or any other suitable support above the boiler is my automatic regulator, of which 10 designates a base plate on which is rigidly mounted 105 an ordinary alarm clock 11. Rising from 110

the base plate 10 are a pair of standards 12 and 13, in which is journaled a shaft 14, one end of which is coupled at 15 to the alarm winder 16 of the clock, while its other end carries an operating handle 17. Also mounted on the base 10 are a pair of standards 18 and 19, in and between which is journaled a countershaft 20. Fast on the shaft 14 is a spur pinion 21 which meshes with a spur gear 22 that is keyed on the shaft 20, as clearly shown in Fig. 4. Loose on the shaft 20 at one side of the gear 22 is a winding drum or spool 23, on which is wound a cord 24 that extends down to and is connected with the free edge of the draft door 6, as clearly shown in Fig. 1.

On one end of the drum 23 is formed a clutch member 25; and splined on the shaft 20 so as to slide lengthwise of the latter is a co-operating clutch member 26 normally urged into engagement with the clutch member 25 by a spring 27. As shown, the hub of the clutch member 26 is formed with a longitudinal slot 28 that is engaged with a cross-pin 29 fixed in the shaft 20 whereby the clutch member 26 is keyed to the shaft for rotary movement with the latter, but is permitted sufficient play lengthwise of the shaft to effect engagement and disengagement of the clutch members. The clutch member 26 is formed with an annular groove 30, in which is fitted a ring 31 having a depending shank 32, continuous with which latter is a horizontal extension 33 that passes through the upright 19 and at its outer end is pivotally connected at 34 to a cam 35, the working face of which latter operates against the outer surface of the upright 19. The cam 35 is formed with an integral arm or handle 36 that extends through a vertical slot in a keeper bracket 37 attached to the outer side of the post 19, whereby the arm or handle of the cam is guided and supported laterally so as to swing only in a vertical plane. To the free end of the cam handle 36 is connected a chain or cord 38 that extends upwardly over one or more guide pulleys 39, thence downwardly, and is connected at 40 to one end of the diaphragm governor lever 8.

When the boiler is adjusted to maintain a low fire, under which no steam is generated, the parts are in the relative positions illustrated in Fig. 1 and by full lines in Figs. 2 and 3. When the alarm is sprung at the predetermined hour in the morning, the alarm winder 16, through the gears 21 and 22, shaft 20 and clutch 26, 25, winds the cord 24 upwardly, thereby raising the draft door 6. As soon as steam has been generated, the pressure thereof acting on the diaphragm governor 7, swings the lever 8 in a manner to draw downwardly on the chain or cord 38 attached thereto. This rocks the

cam arm 36 upwardly, as shown by dotted lines in Fig. 2, causing the cam 35, through engagement with the post 19, to pull the clutch member 26 out of engagement with the clutch member 25, thereby leaving the winding drum 23 free on the shaft 20 and permitting the draft door 6 to fall to closed position.

While I have shown and described a specific embodiment of my invention, it will be manifest that the details of construction and arrangement may be variously modified without involving any departure from the invention or sacrificing any advantages thereof. Hence, I reserve all such variations and modifications as fall within the spirit and purview of the appended claims.

I claim:

1. In a time-controlled draft regulator for boilers, the combination of an alarm clock, a winding shaft directly coupled to the alarm winder of said clock, a pinion on said winding shaft, a countershaft, a gear on said countershaft meshing with said pinion, a winding drum on said counter shaft, and a cord extending from said winding drum to a draft regulating element of the boiler.

2. In a time-controlled draft regulator for boilers, the combination of an alarm clock, a winding shaft directly coupled to the alarm winder of said clock, a pinion on said winding shaft, a countershaft, a gear fast on said countershaft meshing with said pinion, a winding drum loose on said countershaft, a cord extending from said winding drum to a draft regulating element of the boiler, a clutch normally coupling said drum to said countershaft, and means actuated by steam pressure generated in the boiler for disconnecting said clutch.

3. In a time-controlled draft regulator for boilers, the combination of an alarm clock, a winding shaft directly coupled to the alarm winder of said clock, a pinion on said winding shaft, a counter shaft, a gear fast on said countershaft meshing with said pinion, a winding drum loose on said countershaft, a cord extending from said winding drum to a draft regulating element of the boiler, a clutch member rigid with said drum, a mating clutch member splined on said countershaft, a spring urging said clutch members into coupled relation, and means actuated by steam pressure generated in the boiler for retracting said last-named clutch member against the thrust of said spring.

4. In a time-controlled draft regulator for boilers, the combination of an alarm clock, a winding shaft directly coupled to the alarm winder of said clock, a pinion on said winding shaft, a countershaft, a gear fast on said countershaft meshing with said pinion, a winding drum loose on said countershaft, a cord extending from said wind-

- ing drum to the draft door of the boiler, a clutch member on one end of said drum, a mating clutch member splined on said countershaft, a spring urging said last-named clutch member into coupled relation to said drum, a cam, a connection from said cam to said spring-actuated clutch member for retracting the latter, and means actuated by steam pressure generated in the boiler for actuating said cam.
5. In a time-controlled draft regulator for boilers, the combination of an alarm clock, a winding shaft directly coupled to the alarm winder of said clock, a pinion on said winding shaft, a countershaft, a gear fast
- on said countershaft meshing with said pinion, a winding drum loose on said countershaft, a cord extending from said winding drum to the draft door of the boiler, a clutch member on one end of said drum, a 20 mating clutch member splined on said counter shaft, a spring urging said last-named clutch member into coupled relation with said drum, a cam, a connection from said cam to said spring-actuated clutch member 25 for retracting the latter, and a pull cord connecting said cam to the diaphragm governor lever of the boiler.

OSCAR LINDHOLM.
